UNITED STATES PATENT OFFICE

101,473

DESIGN FOR A BUILDING

Arthur C. Stalcup, Tyler, Tex.

Application July 24, 1936, Serial No. 64,016

Term of patent 14 years

To all whom it may concern:

Be it known that I, Arthur C. Stalcup, a citizen of the United States of America, residing at Tyler, county of Smith, and State of Texas, have invented a new, original, and ornamental Design for a Building, of which the following is a specification, reference being had to the accompanying drawing, forming part thereof, wherein:

Figure 1 is a side elevation of a building, showing my new design.

Figure 2 is a side elevation illustrating the reverse side of a building.

Figure 3 is a top plan view, and
Figure 4 is an end elevation.

I claim:

The ornamental design for a building, as shown and described.

ARTHUR C. STALCUP.
